COLLAR CONSTRUCTION FOR TEAR STRIP TYPE OF RECLOSEABLE CONTAINERS

John E. Socke, Pelham Manor, N. Y., assignor to
American Can Company, New York, N. Y., a
corporation of New Jersey

Application December 11, 1944, Serial No. 567,667

4 Claims. (Cl. 220—54)

1

The present invention relates to a metal hermetically sealed or air-tight tearing strip container or can having one or more interior collars arranged inside of the can and has particular reference to a multiple part body having sections spaced apart but secured to the collar or collars in one or more circumferential joints which can be soldered from the exterior of the container and the container after opening can be hermetically resealed by a replaceable air-tight reclosure cover.

The usual tearing strip collar container after opening can be recovered as contradistinguished from resealed by the detached can end or cover. This being so it is not necessary that the collar be joined to the can body in a sealed joint and usually in such cans the collar is merely beaded into the body wall. There are times, however, when an air-tight reclosure for cans of this general type is desirable and the first thought as to manufacture, naturally, is directed to the hermetic joining of the body and the interior collar. Soldering of the collar to the can body would appear to make for a simple and efficient air-tight reclosure at such junction but soldering necessarily must be carried out on the inside of the can body and this presents many manufacturing difficulties.

The present invention contemplates the forming of the body member by joining two or more separate complete tubular can body sections through the intermediacy of one or more interior beaded collars in such a manner as to cause the bead of the collar to function as a spacer element for the adjacent body elements, this construction exposing the adjoining edges of the body sections as well as the collar bead on the outside so that an efficient soldered joint may be easily made at this connection by exterior soldering.

An object of the invention is the provision of a multiple part container body joined together by one or more connecting interior collars and providing a container in which the body sections are spaced apart by the collars with the lines of juncture exposed to the outside or container exterior from which it is soldered.

Another object of the invention is the provision of a reclosure tearing strip container constructed of two independent body sections and a connecting interior collar all joined in an exteriorly soldered joint in which after opening of the container by removal of the tearing strip, the opened container is reclosed in an air-tight joint by sealing the collar.

Still another object is the provision of a tearing strip collar container of the character de-

2

scribed in which the collar carries a reclosure cover sealed within the can, so that the opened can after removal of the tearing strip may be reclosed in an air-tight joint by the reclosure cover which is exposed to access for resealing purposes by initial opening of the can.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a multiple body soldered container embodying the present invention;

Fig. 2 is an enlarged sectional view taken substantially along section line 2—2 in Fig. 1; and

Fig. 3 is a view similar to Fig. 2, but of the opened container after removal of the tearing strip and showing the resealing of the can for reclosure purposes by a replaceable engagement with the collar in an air-tight joint.

The present invention embodies a container formed of a plurality or multiple number of independent can bodies. As exemplified in the drawings, these body parts may consist of a body section 11 and a body section 12. The body sections are each frictionally fitted on a connecting interior collar 13. This collar is beaded as at 14 and the bead preferably acts as a spacer for the adjoining bodies whereby the outside of the bead is exposed on the exterior of the container. This construction makes for easy soldering of the parts as at 15 by application of the solder to the outside wall and thus lends itself to a rapid commercial soldering operation. Obviously if a longer can is desired more than two can body sections can be used with the necessary number of connecting collars.

An end closure 17 is secured to the top end of the body section 11 and on the bottom end of the body section 12 an end closure 18 is similarly secured. Such end joints may be formed as the usual double seams having interposed conventional gaskets or compound lining material 19 for making the joints hermetic.

Above the bead 14, the body section 11 is scored with a pair of parallel score lines which include a lower score line 21 and an upper score line 22 setting off a tearing strip 23. At the side seam of the container the tearing strip terminates in a tongue 24 which provides for engagement of the usual opening key. The two score lines 21, 22, preferably are cut on the interior wall of the body in the usual manner.

From the beaded portion 14, the collar 13 extends along the interior of the body section 11, this being one of the tightly fitting parts of the collar. At the lower score line 21 the collar wall extends inwardly and upwardly in a double rounded corner 25 which merges into a cylindrical vertical wall 26 spaced inwardly from the body wall. In other words this wall 26 is of a smaller diameter. At the top the interior wall 26 terminates in an inwardly extending reclosure curl 27 which provides a smooth mouth and reclosure seat for the opened container. The body wall 11 above the upper score line extends into the upper double seam locality 19, this portion of the body wall being designated by the numeral 31.

A reclosure cover 35 is contained within the can and is of such construction as to be lightly carried on the interior collar 13 when the can is sealed initially but is made usable as a reclosure member when the container is opened by removal of the tearing strip 23. This cover has a depending cylindrical skirt 36 which terminates in an outwardly extending edge curl 37 at the bottom. The diameter of the skirt 36 is greater than that of the collar wall 26 which it embraces.

At the top the skirt portion 36 merges into an annular arched channel section or groove 38 connecting by an integral rounded corner 41 with a flat integral annulus 42 which at the inside merges into a conical wall 43. At the inside and at the top the conical wall 43 extends by a gently curved corner 44 into a central panel 45. Preferably the plane of the central panel 45 passes through the top of the arched section 38 so that the cover 35 constitutes in effect a flush cover. Cooperating threads 48, 49 are formed respectively in the collar wall 26 and in the cover skirt 36.

A sealing gasket 51 is disposed in the annular groove formed on the under side of the arch wall 38. At the time the can is ready to be initially closed by seaming of the top end or cover 17 at 19, the reclosure cover is preferably loosely applied to the collar 13. The gasket 51 thus applied lightly engages the curl 27 of the collar, as shown in Fig. 2. The gasket 51 is concerned with the reclosing of the opened container and this light engagement is only a carrying position. When the top cover is seamed onto the can and it is fully sealed (as in Fig. 2) there is no danger of the enclosed reclosure cover 35 becoming unscrewed even though it is only loosely applied, as the outer cover 17 prevents such displacement.

Upon removal of the tearing strip 23, the top end closure 17 together with the detached body wall part 31 may be thrown away as no longer of service. The can then is fully opened for dispensing usually a portion of its contents by unscrewing the reclosure cover 35. The opened container thereafter may be hermetically sealed as often as desired merely by threadedly engaging the cover and the collar threads and rotating the cover. By screwing down tightly, the gasket 51 is caused to press down against the collar curl 27 so that the curl becomes embedded in the gasket as a replaceable reclosure seat.

It will be understood that a separate reclosure cover 35 which is sealed entirely within the container is shown herein by way of example only. While it is not essential to have a reclosure element for a can composed of multiple body sections as shown in the present invention it is desirable by reason of the fact that the instant disclosed improvement of joining adjacent body

sections by means of an interposed interior collar insures that the collar can be easily and efficiently soldered within the body.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a sealed air-tight sheet metal container, a multiple section container body having adjacent sections thereof spaced apart, an interior spacer collar for joining adjacent body sections, the ends of adjacent body sections tightly fitting over said collar and leaving exposed the outer surface of the collar between the body sections, end closures secured to the opposite outer ends of said container body, a metallic fused bond between the fitted collar and the adjacent body section surfaces to provide an air-tight container joint, and a separable rotatable reclosure cover seated upon an exposed end of said collar spaced inwardly from one of said secured end closures and entirely confined within the sealed container.

2. In a sealed air-tight sheet metal container, a multiple section container body having adjacent sections thereof spaced apart, an interior spacer collar having an integral circumferential outwardly extending bead for joining adjacent body sections, the ends of body sections tightly fitting over said collar and leaving exposed the outer surface of the collar bead where it fits between the body sections, end closures secured to the opposite ends of said container body, a solder bond interposed between the fitted collar and the body section surfaces adjacent the exposed beaded surface of said collar to provide an air-tight container joint, and a separable rotatable reclosure cover seated upon an exposed end of said collar spaced inwardly from one of said secured end closures and entirely confined within the sealed container.

3. In a sealed air-tight sheet metal container capable of air-tight reclosure, a multiple section container body having adjacent sections thereof spaced apart, one section having score lines defining a removable tearing strip for opening the container, an interior beaded spacer collar for joining adjacent body sections, the ends of adjacent sections tightly fitting over said collar with the collar bead interposed therebetween to expose an outer surface part of the collar, end closures hermetically secured to the opposite ends of said container body, a solder bond interposed between the fitted collar and the body section surfaces to provide an air-tight container joint, and a reclosure member seated upon and having threaded connection with said spacer collar for reclosing the container in an air-tight joint after the container is initially opened by removal of said tearing strip, said reclosure member being confined entirely within said sealed container.

4. In a sealed cylindrical air-tight sheet metal container capable of air-tight reclosure, a container body formed of two similar body sections of the same diameter, one of said body sections having score lines defining a removable tearing strip for opening the container, end closures for sealing the opposite ends of said body, an interior spacer collar tightly fitting within adjacent ends of said body sections to form a joint for the

body sections, a portion of the collar in the space between the body sections being exposed on the container exterior, said collar extending inwardly to provide a cylindrical wall terminating in a reclosure curl spaced inwardly from the body wall, a solder bond interposed between the fitted collar and the body section surfaces to provide an air-tight container, a reclosure cover seated on said cylindrical collar wall and confined inside of the sealed container, said cover having a depending cylindrical wall fitting over said cylindrical collar wall, and cooperating threads respectively on the cylindrical walls of said collar and said reclosure cover, said threads being rendered operative by removal of said tearing strip in initially opening the container for forming an air-tight seal at said reclosure curl, thus hermetically reclosing the opened container.
